UNITED STATES PATENT OFFICE.

EMIL E. NOVOTNY, OF PHILADELPHIA, PENNSYLVANIA, ASSIGNEE TO JOHN STOG-
DELL STOKES, OF SPRING VALLEY FARMS, HUNTINGTON VALLEY POST OFFICE,
PENNSYLVANIA.

PROCESS OF CURVING PRINTING PLATES.

Original application filed February 9, 1926, Serial No. 87,111. Divided and this application filed
November 19, 1926. Serial No. 149,453.

This invention relates to a process of producing curved printing plates. The method is particularly directed to the curving of a particular type of printing plate wherein the 5 printing plate comprises a special, non-homogeneous sprayed metal having great thermoplasticity.

The present application is a division of my copending application, Serial No. 87,111, filed 10 February 9, 1926, for "printing plate and method of making the same."

Briefly stated, my method is directed to the curving of metallic printing plates formed through the action of a metallic spray 15 so adjusted that a porous, non-homogeneous structure will be produced. This printing plate body, because of its lack of homogeneous qualities, is capable of being rendered thermoplastic by being heated to a temperature 20 well below its melting point and may therefore be curved by merely being heated upon a suitable mandrel, the weight of the printing plate itself being sufficient for this purpose. This great thermoplasticity at a temperature 25 well below its melting point permits of curving metallic printing plates or printing plates comprising a metallic body without undue distortion and results in a true curve which will cling to the cylinder 30 of the press throughout its area. A slight pressure, however, is most desirable and therefore I prefer to produce the curving under the combined action of heat and pressure. By applying pressure and providing a 35 suitably curved form the printing plate may at the same time be leveled or have the make-ready incorporated therein during the act of curving the same. The process therefore makes possible the curving of plates with a 40 minimum amount of distortion and permits at the same time the introduction of the regularities and irregularities required for high grade printing. This is an advantage not only from the standpoint of saving in operations 45 but at the same time insures that a plate having been leveled at the time that it is curved will not have such leveling or make-ready distorted or destroyed because of a subsequent curving operation. My copending 50 application, Serial No. 149,452 filed November 19, 1926, for "process of correcting printing plates," which is also a division of my copending application Serial No. 87,111,

filed February 9, 1926, claims specifically the leveling operation. 55

After long experimentation with eutectic alloys in the form of foil and plastic metal, I have discovered that an alloy such as foundry type, monotype, or similar metals including various alloys comprising metals 60 such as lead, tin and antimony, is most useful for my purpose. These alloys when applied to a suitable original by means of a metallic spray properly adjusted form a structure which is not homogeneous, and the 65 particles are therefore combined in a structure having a smooth, clean, polished working face but a body of more or less open porous structure. The particles upon striking the surface of a properly prepared matrix 70 deposit thereon without rebounding therefrom and form small, thin, scalelike portions, apparently having oxidized faces, the oxide or perhaps the cooling of the thin sections 75 preventing the formation of a solid homogeneous welded body. Apparently, too, where alloys are used, certain of the lowest melting components, such as the eutectic alloys of the composition, are thrown out to the edges and these tend to hold the structure in form, with 80 the addition, however, of a certain intermeshing or commingling of the odd size particles of the spray. Be that as it may, however, actual experimentation has proven that these 85 non-homogeneous plates, whether made of an alloy or of a solid metal but so long as they are sprayed in an open no-homogeneous manner, will display remarkable thermoplastic properties. This is very well covered in my copending application previously referred to, 90 Serial No. 87,111, filed February 9, 1926.

Even though the printing plate should have a relatively tough facing section formed by depositing harder metals either by means of the spray or by means of an electrolytic 95 deposit, the body portion when made by my spray method will still retain its thermoplastic properties, and therefore it is not essential that the printing plate be made entirely of non-homogeneous material as it may be a 100 composite structure.

This composite structure may comprise a plate consisting of similar materials throughout but having a fine deposit on its face section followed by a relatively coarse deposit 105 for the backing or body section, or may con-

sist of dissimilar materials such as, for example, the application of a harder and tougher material for the working face. In other words, a printing plate comprising substantially a body portion of sprayed metal having open, porous, non-homogeneous characteristics is useful for my purpose.

In the accompanying drawings—

Fig. 1 is a cross sectional view of a printing plate made by my method wherein a fine face spray is first applied and which is subsequently backed with a coarser sprayed body forming section.

Fig. 2 is a cross sectional view of a modified form of printing plate similar to that shown in Fig. 1 with the exception, however, that a harder face coating is applied either by means of a spray or by a subsequent electrolytic deposit.

Fig. 3 is a perspective view showing the apparatus and plate in position for curving.

This apparatus is indicated as an entirety by B which is supported on a suitable base. This curving apparatus consists essentially of a heated base indicated as an entirety S', having a polished curved base section 18' suitably heated as conventionally shown by the cock 21 for the admission of a suitable heating medium. Pressure is applied by means of the screw arrangement 22 operating against the concave polished platen 23 against the face of the printing plate 18, the back of the printing plate being indicated by 20. Suitable cooling facilities are again provided by means of the opening to the cored out section of the base S' wherein 24 indicates the inlet for a cooling medium and 25 an opening for a suitable outlet. The plate is placed face up upon the heated platen S' until the desired temperature is reached. This for foundry type metal will be about 400 to 500° F. It will be found that the plate when sufficiently heated will have assumed its curved form and that a slight pressure from the platen 23 will cause the plate to assume the curve provided for by the concave section 23 and convex section 18'. For some purposes a suitable blanket may be interposed between the back of the plate 20 and the convex section 18' in order that irregularities may be taken up. By taking up these irregularities against the face of the platen 23, the necessary regularities or irregularities required in a suitable printing plate may be introduced at the same time that the plate is being curved. The plate is preferably set to rigidity by the introduction of a suitable cooling medium such as water circulating through the openings 24 and 25. It will be noted that the concave face portion 23 is preferably not heated as I have found that it is preferable to have this portion of the apparatus relatively cold in order that the printing face may not become marred or mushroomed should the plate become too thermo-

plastic at the printing face portion. It is therefore preferred to cool the face while pressure is being applied in order to curve and level the printing element.

It will, of course, be understood that instead of producing ordinary relief plates by this process, I may produce intaglio plates by the use of suitable originals or by means of ordinary expedients such as, for example, in- 70 version.

While I have herein shown and described certain preferred embodiments of my invention, I wish it to be understood that I do not confine myself to all of the precise details herein set forth, as modifications and variations may be made without departing from the spirit of the invention or exceeding the scope of the appended claims.

What I claim is—

1. The herein described method of producing a curved printing plate which consists in forming a relatively flat plate body of sprayed metallic particles and providing the same with a printing face and then heating such plate below its melting point and curving the heated plate over a suitable form to a predetermined shape. 85

2. The herein described method of producing a curved printing plate which consists in forming a relatively flat plate body of sprayed metallic particles and providing the same with a printing face, heating the plate below its melting point, and curving the heated plate over a suitable form to a desired dimension to obtain a predetermined curve 95 100 while maintaining the dimensions of the printing face of the plate.

3. The herein described method of producing a curved printing plate which consists in forming a relatively non-homogeneous plate 105 body of sprayed metallic particles and providing the same with a printing face, then heating such plate and curving the same over a suitable form to a predetermined shape, and then cooling the plate. 110

4. The herein described method of producing a curved printing plate which consists in forming a relatively flat, porous, non-homogeneous plate body of sprayed metallic particles and providing the same with a printing face, then heating the plate and curving the heated plate in contact with a suitable form, and then cooling the plate. 115

5. The herein described method of producing a curved printing plate which consists in forming a plate body, composed of a section of coarse sprayed metallic particles and a section of fine sprayed metallic particles and providing said plate body with a printing face, then heating the plate below its melting 120 125 point and curving the plate while so heated over a suitable form, and then cooling the plate.

6. The herein described method of producing a curved printing plate which consists 130

in forming a relatively flat, porous, non-homogeneous plate body of sprayed metallic particles and providing said plate with a printing face, then heating the plate and curving the same while heated over a suitable form while producing at the same time desired regularities and irregularities in the printing face, and then subsequently cooling said plate.

Signed at Philadelphia in the county of Philadelphia and State of Pennsylvania this 5th day of November, A. D. 1926.

EMIL E. NOVOTNY.
